RESTAURANT FACADE

Gene Darcy, 10474 Santa Monica Blvd.,
Los Angeles, Calif.

Filed Jan. 27, 1966, Ser. No. 792

Term of patent 14 years

(Cl. D13—1)

Fig. 4

Fig. 2

Fig. 1

Fig. 3

Fig. 5

Fig. 6

FIG. 1 is a front elevational view of a restaurant facade showing my new design;

FIG. 2 is an end view taken from the left of FIG. 1;

FIG. 3 is an end view taken from the right of FIG. 1;

FIG. 4 is a top view thereof;

FIG. 5 is a bottom view thereof; and

FIG. 6 is a rear elevational view thereof.

The front of the restaurant shown in broken lines in FIG. 1 is disclosed for illustration purposes only.

I claim:

The ornamental design for a restaurant facade, substantially as shown and described.
